[57] CLAIM

The ornamental design for a furniture corner protector, as shown and described.

DESCRIPTION

FIG. 1 is a side perspective view of a furniture corner protector showing my design;

FIG. 2 is a side plan view;

FIG. 3 is a top plan view;

FIG. 4 is a front elevational view; and

FIG. 5 is a sectional view taken along the line 5—5 of

The side of the corner protector not shown is a mirror image of the side shown in FIG. 2.
